[57] CLAIM

The ornamental design for an emission electrode holder for electrostatic precipitator, substantially as shown and described.

DESCRIPTION

FIG. 1 is a perspective view of an emission electrode holder for an electrostatic precipitator according to our invention;

FIG. 2 is a front elevational view of the holder of FIG. 1;

FIGS. 3 and 4 are plan and inverted plan views, respectively, of the holder of FIG. 1;

FIG. 5 is a side elevational view of the holder of FIG. 1; and

FIG. 6 is a rear elevational view of the holder of FIG. 1.

FIG. 1.

FIG. 3.

FIG. 5.

FIG. 2.

FIG. 6.

FIG. 4.
